UNITED STATES PATENT OFFICE.

BENJAMIN F. CUMMINS AND JOHN STENWALL, JR., OF CHICAGO, ILLINOIS,
ASSIGNORS TO THE B. F. CUMMINS COMPANY, OF SAME PLACE.

PERFORATING, DATING, AND RECEIPTING STAMP.

SPECIFICATION forming part of Letters Patent No. 475,440, dated May 24, 1892.

Application filed November 9, 1891. Serial No. 411,280. (No model.)

To all whom it may concern:

Be it known that we, BENJAMIN F. CUMMINS and JOHN STENWALL, Jr., citizens of the United States, residing in Chicago, in the 5 county of Cook and State of Illinois, have invented a new and useful Improvement in Perforating, Dating, and Receipting Stamps, of which the following is a specification.

Our invention relates to hand-operated perforating-stamps, and more particularly to improvements upon the perforating-stamp shown and described in Letters Patent No. 409,324, of August 20, 1889, and No. 433,003, of July 29, 1890, wherein a series of independently-15 movable perforating-punches and their female die are employed in connection with a revolute reversely-socketed plunger or matrix for operating only such punches as may be required to make or perforate any particular 20 figure or character. In our said previously-patented machine the characters are printed or perforated one at a time, the revolute matrix or plunger being turned or adjusted to bring a different matrix-face into operation 25 as required for each stroke.

Our present improvement consists in combining with two or more sets or groups of independently-movable perforating-punches and their corresponding single female die-30 plate a single matrix-carrying lever furnished with one or more fixed matrix or plunger faces for printing the non-changeable data—such, for example, as the word "Paid"—and one or more many-faced revolute or adjustable matrices for operating said groups of perforating-punches by one and the same stroke of the 35 operating-lever.

It further consists in combining two or more groups of independently-movable perforating-40 punches with a single guide for all said punches, two or more adjustable reversely-socketed matrices for operating said groups of punches, and a common operating-lever for operating the matrices.

It further consists in the novel devices and 45 novel combinations of parts and devices herein shown and described, and more particularly pointed out in the claims.

In the accompanying drawings, which form 50 a part of this specification, Figure 1 is a side elevation of a device embodying our inven-

tion, the removable cover being shown in section. Fig. 2 is a vertical cross-section on line 2 2 of Fig. 1. Fig. 3 is a vertical longitudinal section on the line 3 3 of Fig. 2. Fig. 4 is a 55 bottom view showing the removable cup or receptacle for receiving the bits of paper punched out in making the perforations. Fig. 5 illustrates the work done by our dating and receiving perforating-stamp. Fig. 6 is a plan 60 view with the cover or outer casing removed.

In the drawings, A represents the bed-plate of the machine.

A' is a frame-plate secured rigidly to the bed-plate A by screws a and to which the 65 guides for the perforating-punches are secured.

B are the independently-movable punches for perforating the paper.

C is the female die secured to the bed-plate 70 A, upon which the sheet of paper rests during the punching operation and into or through which the punches B project.

The punches B are operated by plungers or matrices carried upon an operating-lever F, 75 there being one matrix for each set or group of punches. The adjustable or revolute matrices D are six in number. Two of these are employed to indicate the year, two the day of the month, and two the month. The 80 matrix-rings D each have a series of matrix-faces d, preferably eleven in number, one for each of the ten digits and one blank face. The matrix-faces d are each reversely socketed, so that they will not operate those 85 punches of the group which are not required for printing the particular character desired. The revolute or adjustable many-faced rings D revolve upon a shaft or stud F', secured in the bifurcated end of the lever F by screw- 90 bolts, as f. The matrix-rings D are held in proper position radially for the operation of each of their matrix-faces by locking-pins d', which fit in a series of holes d² in the matrix-rings and enter a registering-slot f' in the 95 shaft F' at the end of the operating-lever.

The fixed or non-adjustable matrices D' and D² are secured rigidly to the operating-lever F, and preferably consist of a central plate fixed to the lower face of the lever F by screws 100 f², flush with the operating-faces d of the series of rings D.

There are eight sets or groups b , b' , and b^2 of the perforating-punches B. The six sets or groups of punches b are operated by the six adjustable or revoluble matrix-rings D, certain of the punches of each group being operated by each of the matrix-faces d of each of the rings D and others not. The group of punches b' is operated by the fixed matrix or plunger D to print in perforated characters the word "Paid," as illustrated in the machine shown in the drawings, and the group or set of punches b^2 is operated by the fixed matrix or plunger D² to print a signature, as "B. F. C. Co." in the machine illustrated in the drawings; but of course, however, it will be understood that these fixed or non-changeable characters which are printed by the sets of punches b' b^2 and the matrices D' D² may be varied as desired or required.

The guides for the series of independently movable punches B consist of two fixed plates G and G', rigidly secured to the frame plate or block A', and a soft-metal filling G², molded in the guide case or receptacle G³ around the punches. The guide case or receptacle G³ is formed integral with the frame-block A'. The frame-block A', which carries the punch-guides, is formed with a shoulder a', so as to leave a space for the insertion of the sheet of paper over the die-plate C and under the guide-plate G. A movable or stripper guide-plate G⁴ reciprocates in the space between the upper guide-plate G' and the soft or molded guide G² and serves to retract or withdraw the punches B by engaging the shoulder B' thereon. The stripper or guide plate G⁴ is operated positively by connection with the operating-lever F through the plates or ears g and cross-bars g', which extend through the guide-case G³ between the groups of punches B. The plates or ears g are attached to the operating-lever F by screws f³. The operating or matrix-carrier lever F is pivoted to ears a² on the frame-block A², which is secured to the frame-pieces A A' by screws a³. The frame piece or block A² has an upright projection or arm A³, to which is pivoted a secondary operating or handle lever H, which is connected by a pivoted link h with the operating-lever F. The link h is eccentrically pivoted at h' to the shaft h² of the lever H, so that the force exerted upon the handle-lever H is multiplied many times when communicated to the matrix-carrying lever F. The handle-lever H is retracted or returned to position by a spring H'.

K is the cup or receptacle for receiving the punchings from the paper. It is provided with an eccentric flange k, and is secured in place by engaging the heads k' of the pins k², fixed in the bed-plate A on the under side thereof. By means of this eccentric or cam-shaped flange k the cup K may be removed and again replaced in position by simply giving it a slight turn.

M is the case for inclosing the stamp and

protecting its mechanism. It is secured to the bed-plate A by screws m. It is furnished with a slot m' for the handle-lever to project through and to permit of its operation. It is also furnished with a removable cap M' for giving access to the locking-pins d', by which the revoluble or adjustable matrix-rings are turned or adjusted, as desired, and locked in position again. This cap M' is furnished with sliding hinge-pins M², which project through holes in the top of the cover M and which are provided with hooks or bent ends m² to support the cap in the position indicated in the dotted lines in Fig. 3.

Intermediate between the sets or groups of punches which perforate the figures indicating the year and the month we arrange a group of punches b³ for printing a period or other division-mark. A similar group b⁴ is arranged between the groups of punches which perforate the characters indicating the day of the month and those indicating the month. The group of punches b³ b⁴ are operated by the matrix-faces d of the matrix-rings D, a part of the punches of each group being operated by each of two adjoining rings D, so that the period or character will be located midway between the year and month characters or the month and day characters, which are separated thereby.

The locking-pins d' are furnished with knobs or handles d³. In operation these locking-pins are utilized as levers or handles for turning the rings D to bring the proper matrix-face into position for operation, the pin being of course first withdrawn from the shaft F'.

The upper guide-plate G' is furnished with an opening or notch g³ in one edge, in which the soft-metal filling G² may be poured into the guide case or receptacle G³ in a molten condition around the punches B, or rather temporary pins put in place thereof, and while the same are in position and while the upper and lower guide-plates G' and G are securely fixed to the frame block or plate A'. As the guide-case G³ for the soft-metal guide or filling G² is formed integrally with the frame-block A' it requires no fixing or adjusting in position independently of said frame-plate A'.

We claim—

1. In a perforating-stamp, the combination, with two or more sets or groups of independently-movable perforating-punches and their corresponding single female die, of a single matrix-carrying lever furnished with one or more fixed matrix or plunger faces, and one or more many-faced revoluble or adjustable matrices for operating said groups of perforating-punches by one and the same stroke, substantially as specified.

2. In a perforating-stamp, the combination, with two or more sets or groups of independently-movable perforating-punches and their corresponding single female die, of a single matrix-carrying lever having two or more

revolute many-faced matrix-rings mounted to revolve upon said lever and simultaneously operated thereby, substantially as specified.

3. In a perforating-stamp, the combination, 5 with a series of sets of independently-movable perforating-punches and their corresponding single female die, of the single operating-lever F, having fixed shaft or stud F', a series of revolute many-faced matrix-rings D, 10 mounted on said shaft F', and fixed matrix or plunger faces D' D² on said lever F, operating conjointly with the matrix-faces of said revolute rings D, substantially as specified.

4. The dating and receipting or canceling 15 perforating-stamp comprising, in combination, six groups b of independently-movable perforating-punches B and two additional groups b' b² of perforating-punches, a female die for all said punches, guides for all said 20 punches, a common operating-lever F, six many-faced revolute matrix-rings D, carried by said lever, and two matrix or plunger faces D' D², also carried by said lever, and a secondary or handle lever H for operating said 25 lever F, substantially as specified.

5. The combination, in a perforating stamp, 30 with a series of groups of independently-movable punches and their corresponding female die, of a guide for said punches, a bifurcated matrix-carrying lever F, having shaft F', and a series of independently-revolute matrix-rings D, mounted upon said lever for operating said groups of punches, substantially as specified.

35 6. The combination, in a perforating-stamp, with a series of groups of independently-movable punches and their corresponding female die, of a guide for said punches, a matrix-carrying lever F, having shaft F', and a series of independently-revolute matrix-rings D, mounted upon said lever for operating said groups of punches, and a series of locking-pins d', passing through holes in said rings and entering registering slots in said shaft F', 45 substantially as specified.

7. The combination, in a perforating-stamp, 50 with a series of groups of independently-movable punches and their corresponding female die, of a guide for said punches, a matrix-carrying lever F, having shaft F', and a series of independently-revolute matrix-rings D, mounted upon said lever for operating said groups of punches, and a series of locking-pins d', passing through holes in said rings 55 and entering registering openings in said shaft F', and a handle-lever H, connected to said lever F by a pivoted link h, substantially as specified.

8. In a perforating-stamp, the combination, 60 with a group of independently-movable punches and their corresponding female die, of a guide for said punches, a reciprocating stripper or guide plate for retracting said punches, a movable plunger or matrix for 65 operating said punches, and devices positively connecting said stripper-plate with said

matrix or plunger, whereby said stripper-plate is positively operated in both directions by said matrix or plunger, substantially as specified.

70 9. The combination, in a perforating-stamp, of a group of independently-movable punches B, their female die C, a guide for said punches, a matrix and matrix-lever for operating said punches, a movable stripper-plate G⁴ for withdrawing said punches, and links g and cross-bars g' g', connecting said stripper-plate directly with said lever F, substantially as specified.

75 10. The combination, in a perforating-stamp, of punches and female die, with a bed-plate A, to which the female die is secured, a frame plate or block A, carrying the guides for the punches, and a separate frame plate or block A², having ears a², to which the operating-lever is pivoted, and the operating-lever and the matrix-disks carried thereby, substantially as shown and described.

80 11. The dating and receipting or canceling perforating-stamp comprising, in combination, six groups b of independently-movable perforating-punches B, a single or common female die for all said punches, guides for all said punches formed in a common guide-block G², a common operating-lever F, six many-faced revolute matrix-rings D, carried 90 by said lever, and a secondary or handle lever H for operating said lever F, substantially as specified.

95 12. The dating and receipting or canceling 100 perforating-stamp comprising, in combination, six groups b of independently-movable perforating-punches B and two intermediate groups b³ b⁴ of perforating-punches, a single or common female die for all said punches, 105 guides for all said punches formed in a common guide-block G², a common operating-lever F, and six many-faced revolute matrix-rings D, carried by said lever, said intermediate group of punches b³ and b⁴ being each in part 110 operated by the matrix-faces of two adjoining rings, substantially as specified.

115 13. In a perforating-stamp, the combination, with bed-plate A, having female die C secured thereto, of frame-plate A', furnished with guide-case G³, soft-metal guide G² therein and upper and lower guides G G' secured thereto, matrix-lever F, and a matrix or plunger carried thereby for operating said punches, frame-block A², having ears a², to which said 120 lever F is pivoted, and said frame-block A², having standard A³, and a handle-lever H, pivoted thereto, for operating said lever F, substantially as specified.

125 14. In a perforating-stamp, the combination, with bed-plate A, having female die C secured thereto, of frame-plate A', furnished with guide-case G³, soft-metal guide G² therein and upper and lower guide-plates G G' secured thereto, matrix-lever F, and a matrix 130 or plunger carried thereby for operating said punches, frame-block A², having ears a², to

which said lever F is pivoted, said frame-block A² having standard A⁸, and a handle-lever H, pivoted thereto for operating said lever F, said handle-lever H being connected to said lever F by a link h and an eccentric pivot h', substantially as specified.

15. In a perforating-stamp, the combination, with bed-plate A, having female die C secured thereto, of frame-plate A', furnished with guide-case G³, soft-metal guide G² therein, and upper and lower guide-plates G G', secured thereto, a movable stripper-plate G, reciprocating in said guide-case G³, matrix-lever F, and a matrix or plunger carried thereby for operating said punches, and links g and cross-bars g', connecting said stripper-plate with said lever F, substantially as specified.

16. The combination, in a perforating-stamp, of a series of groups b b b b b b' b² b³ b⁴, of independently-movable perforating-punches B and their corresponding female die C, a guide for all said punches, a matrix-carrying lever F, furnished with fixed matrix or plunger faces D' D², and a series of revolvable matrix-rings D, having each a series of matrix-faces, said intermediate groups of punches b³ b⁴ being each in part operated by

two adjoining matrix-rings D D, substantially as specified.

17. In a perforating-stamp, the combination, with two or more groups, of independently-movable perforating-punches, with a single guide for all said punches, a common die-plate for all said punches, two or more 35 adjustable reversely-socketed matrices for operating said groups of punches, and a common operating-lever for operating said matrices, substantially as specified.

18. In a perforating-stamp, the combination, with two or more sets or groups of independently-movable perforating-punches b b, of an intermediate group of perforating-punches b³, a common corresponding female die for all of said punches, and a single matrix-carrying lever having two or more revolvable many-faced matrix-rings mounted upon said lever, said intermediate group of punches b³ being part operated by each of two adjoining matrix-rings, substantially as specified.
